UNITED STATES PATENT OFFICE.

JOE CRITES, OF EVANSTON, AND WILLIAM H. VOGEL, OF HIGHLAND PARK, ILLINOIS,
ASSIGNORS TO RAYMOND BROTHERS IMPACT PULVERIZER CO., OF CHICAGO, ILLINOIS,
A CORPORATION OF ILLINOIS.

REGULATOR FOR PULVERIZING MILLS.

Application filed March 2, 1925. Serial No. 12,678.

This invention relates to means for pulverizing fuel, and more particularly to improvements in a pulverizing mill of the impact type, in which a plurality of swinging hammers operate within a substantially cylindrical beater chamber.

The principal object of the invention is to provide improved means for adjusting the fineness of the pulverized material produced, such means being accessible for adjustment from outside the mill, without necessarily stopping the operation of the mill.

More specifically, a rotary regulator is interposed between the beater chamber and the fan chamber of the mill, which acts to retard more or less the passage of coarse material from the beater chamber to the fan chamber. A normally stationary conical ring which surrounds this rotary regulator, is adjustable toward or from the regulator by means which are readily accessible from outside the mill, thus varying the operation of the regulator, and determining its retarding influence upon the material in the air passing therethrough.

The above and other objects and advantages of this invention will be more apparent from the following detailed description of one approved form of the apparatus.

In the accompanying drawings:

Fig. 1 is a central vertical longitudinal section, partly in elevation through the main portions of the mill.

Fig. 2 is a transverse vertical section taken substantially on the line 2—2 of Fig. 1.

Fig. 3 is a perspective view of the conical adjusting ring.

The mill, as here shown, is of the well-known impact type, and comprises a feeding compartment 1, a beater chamber 2 in which the pulverization process takes place, and a fan chamber 3. A horizontal shaft 4 extends centrally through the substantially cylindrical chambers 2 and 3, and is rotatably supported at its ends, outside of the chambers, in bearings 5 and 6. One projecting end 7 of shaft 4 is connected with an electric motor or other suitable driving means. Within the beater chamber 2, the pulverizing mechanism 8, hereinafter more specifically described, is fixedly mounted on rotary shaft 4, and a fan 9 is similarly mounted on shaft 4 within the fan chamber 3.

The material to be pulverized is maintained within a hopper or other storage receptacle, the lower end of which is indicated at 10, and the flow of material from this receptacle into feeding compartment 1, is regulated by the slide valve 11. Below the valve 11, a pocketed feed wheel 12 is mounted on a shaft 13 to rotate in a clockwise direction, Fig. 1, and thus steadily feeds measured quantities of the material into the lower portion of feeding compartment 1 and thence through inlet opening 14 into the inlet end of beater chamber 2. The shaft 13 is intermittently driven at an adjustable slow speed, by a mechanism not shown, from the shaft 15 in the lower portion of the mill housing, which shaft 15 is driven through suitable reduction gearing and the belt 16 from the main rotary shaft 4.

The pulverizing mechanism 8 comprises a plurality (here shown as three duplicate radial series), of beaters or hammers 17, pivotally mounted at their inner ends 18 for limited swinging movement, within a frame or spider composed of a series of plates or discs 19 keyed on shaft 4. These plates 19 are spaced apart by rings 20, and are clamped in assembled position with the rings 20 upon shaft 4, between the fixed collar 21 on said shaft, and a nut 22 adjustable along said shaft 4. Suitable liner members (not here shown) are preferably arranged about the path of travel of hammers 17, and within the enclosing wall of the beater chamber 2, and the material is pulverized partially by the impact of the hammers 17, and partly by being projected by centrifugal force against these liner members.

The fan 9 withdraws the pulverized material suspended in air from beater chamber 2 through the outlet opening 23, into fan chamber 3, and projects this fuel-laden air through conduit 24 to a suitable storage bin or directly to the burners where it is consumed. Air is supplied to the beater chamber 2, from the inlet pipe 25 and through feeding compartment 1, and additional air may be supplied to fan chamber 3 through an adjustable inlet opening 26.

Mounted on shaft 4 adjacent the opening 23 between beater chamber 22 and fan chamber 3, is the rotary regulator 27, comprising a central spider and a series of radially disposed plates 28. The ends of these plates 28

are preferably inclined as shown at 29, and positioned to travel within a short distance of the inner face of the conical ring 30, which forms the inner directing wall of outlet 23. The action of this regulator is to reduce very materially the amount of coarse material in the air passing through outlet 23 into the fan chamber. This regulator acts as a fan for continuing the rotary movement 10 of the contents of beater chamber 2 about the axis of shaft 4, and by centrifugal force throws the material against the diagonally disposed face of ring 30 from which it is thrown back into the beater chamber. The 15 amount of coarse material in the air entering the fan chamber 3 from the beater chamber 2, is consequently very small as compared with the amount that would pass were this regulator 27 not used.

20 In previous mills of this general type, the operation of the regulator 27 has been varied by adjusting the regulator along shaft 4 toward or from the fixed conical ring 30. This of necessity involves stopping the 25 mill and opening the same in order to get at the regulator 27 which is completely enclosed by the mill housing.

According to the present invention, this adjustment of the retarding effect of the regulator is obtained by leaving the regulator 27 in fixed position on the shaft 4, but moving the conical ring 30 toward or from the regulator, axially of shaft 4. The conical surface 30 is provided on the inner side of an 35 annular frame 31, the cylindrical outer periphery of which fits snugly within a corresponding cylindrical passage 32, in the mill housing 33. Outlet opening 23 is provided in the base of frame 31 adjacent the 40 smaller end of conical surface 30. A plurality, here shown as three, of diagonally arranged slots 34 are provided in the cylindrical peripheral surface of annular member 31, and suitably fixed lugs, such as the 45 projecting ends 35 of screws 36, are engaged in these slots 34. The screws 36 may conveniently be mounted in the mill housing 33. It will be noted that if the annular member 50 31 be rotated through a small arc, the lugs 35 and slots 34 will function as cams or screw-threads, to move the ring 31 to and fro axially of shaft 4, along the passage 32. To conveniently accomplish this movement of annular member 31, a lug 37 is provided 55 on this annular member which projects between the inner ends of a pair of adjusting screws 38, mounted in lugs 39 of the fixed mill housing 33. By suitably adjusting the screws 38 which are readily accessible from 60 outside of the mill, the lug 37 and consequently the ring 31 may be rotated through a small arc, thus moving the conical surface 30 toward or from the ends 29 of the blades 28 of the rotary regulator 27. Obviously, when the conical ring 30 is adjust-

ed toward the left, Fig. 1, that is, closer to the regulator 27, it will be more difficult for the coarse material to pass thereby without being thrown out against the conical ring 30 and thence back into the beating zone of the 70 mill, and the fuel will be pulverized more finely by reason of its being retained a much longer time in the beater chamber 2. By adjusting the conical ring 30 towards the right, Fig. 1, away from regulator 27, the passage of material thereby is facilitated, and the fineness of the pulverized material correspondingly decreased.

It will be apparent that these adjustments may be made without dismantling the mill, 80 and even without stopping the operation thereof. By properly proportioning and positioning the slots 34 and the lugs 35 the longitudinal movement of ring 31 axially of shaft 4 may be so limited that it is impossible to bring the ring 30 into contact with the rotating blades 28 and hence there is no possibility of injury to the apparatus even though the mill is in continuous operation.

We claim:

1. A pulverizing mill comprising a beater chamber having an outlet for the pulverized material, a rotary regulator mounted within the chamber adjacent the outlet, 95 and means surrounding the regulator within the outlet and adjustable from outside the chamber for varying the effective size of the outlet with respect to the rotary regulator.

2. In a pulverizing mill comprising a beater chamber having an outlet for the pulverized material, a rotary regulator mounted adjacent the outlet, and a ring member surrounding the regulator and adjustable toward or from the same to vary the flow of material past the regulator.

3. In a pulverizing mill comprising a beater chamber having an outlet for the pulverized material, a rotary regulator mounted adjacent the outlet, and a ring member having a conical opening surrounding the regulator and adjustable toward or from same to vary the flow of material past the regulator.

4. In a pulverizing mill comprising a beater chamber having an outlet for the pulverized material, a regulator of fixed dimensions positioned within the outlet for retarding the flow of pulverized material through the outlet, and means adjustable from outside the chamber for varying the effective size of the outlet with relation to the retarding regulator.

5. In a pulverizing mill comprising a beater chamber having an outlet for the pulverized material, a rotary regulator of fixed diameter positioned for rotation within the outlet for retarding the flow of pulverized material through the outlet, and

means adjustable from outside the chamber for varying the axial clearance between the rotary regulator and the surrounding walls of the outlet.

5 6. In a pulverizing mill comprising a beater chamber having an outlet for the pulverized material, a rotary regulator mounted adjacent the outlet, a ring member mounted in the outlet and having a 10 conical opening surrounding the regulator, and means for rotating the ring in the outlet and thereby moving same laterally toward or from the regulator.

7. In a pulverizing mill comprising a 15 beater chamber having an outlet for the pulverized material, a rotary regulator mounted adjacent the outlet, a ring member mounted in the outlet and having a conical opening and surrounding the regulator, 20 operating cam means on the ring and stationary mill-housing whereby rotary movement of the ring will cause the ring to be moved laterally toward or from the regulator, and means accessible from outside of 25 the chamber for rotating the ring.

8. In a pulverizing mill comprising a beater chamber having an outlet for the pulverized material, a rotary regulator mounted adjacent the outlet, a ring member mounted in the outlet and having a 30 conical opening surrounding the regulator, there being a plurality of inclined slots in the peripheral surface of the ring, and a plurality of fixed lugs projecting into these 35 slots, whereby a partial rotary movement of the ring will cause a lateral movement thereof toward or from the regulator, and means accessible from outside the mill for rotating the ring.

40 9. A pulverizing mill comprising a beater chamber, a shaft extending centrally therethrough, a plurality of pulverizing

hammers mounted on the shaft, the material to be pulverized being fed in at one end of the chamber, the chamber having an outlet around the shaft at the other end thereof, means for withdrawing the pulverized material suspended in air through this outlet, a rotary regulator mounted on the shaft adjacent the outlet, and means surrounding the regulator and adjustable from outside the chamber for varying the effective size of the outlet with respect to the regulator.

10. A pulverizing mill comprising a beater chamber, a shaft extending centrally therethrough, a plurality of pulverizing hammers mounted on the shaft, the material to be pulverized being fed into one portion of the chamber, the chamber having an outlet around the shaft at one end thereof, 55 means for withdrawing the pulverized material suspended in air through this outlet, a rotary regulator mounted on the shaft adjacent the outlet, and a ring member surrounding the regulator and adjustable toward or from same to vary the retarding effect of the regulator.

11. A pulverizing mill comprising a beater chamber, a shaft extending centrally therethrough, a plurality of pulverizing hammers mounted on the shaft, the material to be pulverized being fed into one portion of the chamber, the chamber having an outlet around the shaft at one end thereof, means for withdrawing the pulverized 70 material suspended in air through this outlet, a rotary regulator mounted on the shaft adjacent the outlet, and a ring member having a conical opening surrounding the regulator and adjustable axially of the shaft to 75 vary the retarding effect of the regulator.
